L. P. REIMANN

LADDER BRACKET

Filed March 13, 1922

Inventor:

Louis P. Reimann,

By Emil Kuehne
Attorney.

Witness:
J.J. Oberst,

UNITED STATES PATENT OFFICE.

LOUIS P. REIMANN, OF BUFFALO, NEW YORK.

LADDER BRACKET.

Application filed March 13, 1922. Serial No. 543,224.

To all whom it may concern:

Be it known that I, LOUIS P. REIMANN, a citizen of the United States, residing at Buffalo, in the county of Erie and State of New York, have invented certain new and useful Improvements in Ladder Brackets, of which the following is a specification.

My invention relates to ladder brackets, such as are applied to ladders and used by painters, carpenters, and other artisans to support planks on which to walk while working.

The object of my invention is to provide a bracket of this kind whereby the main strain is imparted to the rails of the ladder; in contradistinction to the present type of bracket, by the use of which the strain is applied to the rungs of the ladder.

Another object of my invention is the provision of a bracket which is adjustable to different widths of ladders, and the plank-support of which may be easily and conveniently adjusted to horizontal position regardless of the inclination of the ladder to which the bracket is applied.

A still further object is to provide a bracket of this kind which is simple, inexpensive and easily attached to a ladder, and which is also durable and readily adjustable along the length of the ladder.

The invention consists in the novel features of construction and in the arrangement and combination of parts to be hereinafter described, and more particularly pointed out in the subjoined claims.

In the drawings:—

Fig. 1 is a perspective view of a ladder shown leaning against a wall and having my improved bracket applied thereto.

Fig. 2 is an enlarged transverse section taken on line 2—2, Fig. 1.

Fig. 3 is a detached perspective view of one of the securing parts of the bracket.

Fig. 4 is a detached perspective view of the other securing part of the bracket.

Fig. 5 is a sectional elevation of the lower portion of the leg forming part of one of the securing parts of the bracket.

Fig. 6 is a detached perspective view of the plank-support and its connected brace, both of which may be said to constitute the supporting portion of the bracket.

Fig. 7 is an enlarged transverse section taken on line 7—7, Fig. 6.

Fig. 8 is an enlarged transverse section taken on line 8—8, Fig. 6.

The reference numeral 10 designates an ordinary ladder having the spaced rails 11 and rungs 12 connected to said rails. The device comprises a securing-portion 13 and a supporting portion 14, the securing-portion being substantially of T-formation and comprising a transverse head 15, and a stem or leg 16 depending from said transverse head at a point between its ends.

The securing-portion is formed in two parts 17, 18, part 17 forming a part of the head while part 18 comprises the stem or leg 16 and a second part of the head 15.

The part 17 of the securing-portion is preferably formed of a flat strip of metal having one end provided with a rearwardly-extending U-shaped portion 19 adapted to straddle one of the rails of the ladder, and it is also provided with a longitudinally-disposed slot 20.

The part 18 of the securing-portion has a flat transverse part 21 adapted to overlie a portion of the part 17. The outer end of said flat transverse part 21 is bent into U-shape, as at 22, and this U-shaped portion is similar to the U-shaped portion 19 and adapted to straddle the other rail of the ladder.

The inner end of said flat transverse part 21 has rearwardly-directed flanges 23 at opposite longitudinal edges adapted, respectively, to bear against the upper and lower edges of the part 17. The stem or leg 18 is preferably integral with the flat transverse part 21 and extends from the lower edge of the latter. Directly below said part 21, said stem or leg is provided with laterally extending arms 24 bent forwardly at their outer ends to form ears 25 provided with pivot holes 26, for a purpose to appear hereinafter.

Formed in the flat transverse part 21 is a bolt hole 27, which is preferably in line with the stem or leg 18, and through which bolt hole and the slot 20 in the part 17, a bolt 28 is passed, said bolt being inserted from the rear so as to first pass through said slot and then through the bolt hole 27 and project through the latter. A thumb nut 29 is applied to the projecting end of the bolt 28 to clamp the two parts 17 and 21 of the head together after adjusting said parts to bring the U-shaped ends 19 and 22 thereof in proper spaced relation so as to fit the rails 11 of the ladder, said U-shaped parts being applied to said rails from the rear. The stem or leg has two supporting hooks 30 at the rear which are preferably stamped from

the metal forming said stem or leg. The hooks 30 are spaced apart to fit adjacent rungs of the ladder, and as the spacings of the rungs on ladders are usually alike, the device receives support from two rungs. If, however, the device should be used with a ladder having its rungs spaced apart a greater or lesser distance than the spacing of the hooks 30, the device will be supported by a single hook only. Therefore, if desired, the device may be constructed with a single hook, but I preferably make the stem or leg 18 of sufficient length to permit the use of at least two supporting hooks.

15 The stem or leg has an outwardly-directed flange 31 along a portion of its length at one edge thereof, and this flange is provided with a series of oblique notches 32 for co-action with a part of the supporting portion 14 of the bracket, to be presently described.

20 The supporting portion 14 comprises an arm or plank support 33 and a brace 34, said arm or plank support being preferably formed of a strip of metal slit at opposite ends and bent lengthwise upon itself, as at 35, so that it is of substantially U-shape along the greater portion of its length, opposite sides of the arm or plank support being bent or inclined outwardly and rearwardly where slit at its rear or inner end, as at 36, and thence directed rearwardly parallel with the U-shaped portion of the arm or plank support, as at 37. In this manner 25 a comparatively large fork is formed at the rear end of said arm or plank support. This fork may be referred to as comprising two spaced arms, parts of which are disposed obliquely and parts parallel with the U-shaped portion of said arm or plank support, the parts parallel with said U-shaped portion having pivot holes 38 which register with the pivot holes 26 in the ears 25.

30 As clearly shown in Fig. 1, the rear or inner ends of the arms forming said fork are spaced to lie against the inner sides of the ears 25, and pivot bolts 39 or any other means for pivotally connecting the plank support to said ears are passed through the pivot holes 26 and 38 formed, respectively, in said ears and the spaced arms at the rear of said plank support.

35 By slitting the opposite or outer end of the plank support, two spaced arms are provided which form a comparatively small fork 40 at said end through which the brace 34 is passed, a pivot 41 being passed through the spaced arms of said fork 40 and brace to pivotally connect the two together.

40 As clearly shown in Figs. 1 and 6, the brace extends upwardly a distance above the top of the plank support so that when a plank rests upon said support it cannot slide outwardly over the end of the same.

45 The upwardly-extending portion of the

brace, designated by the numeral 42, may therefore be considered a safety device for the plank.

The inner or lower end of the brace 34 is forked and has a retainer pin 43 extending through the space within said fork, said pin being adapted to be entered in any one of the oblique notches 32 formed in the flange 31 on the stem or leg 18.

50 The inclination of the ladder to which the device is applied will determine the particular notch 32 of the flange with which the pin 43 of the brace 34 is adapted to engage, it being desirable to have the plank support 33 positioned horizontally at all times in order to make it convenient for workmen to move freely along the plank resting thereon. Therefore, when the ladder is inclined at a greater angle than shown in Fig. 1, it will be necessary to enter the pin 43 in a lower notch of the flange 31 in order to bring the plank support 33 in horizontal position, and when the ladder is positioned to more closely approach the vertical, it will be necessary to enter the pin 43 in a higher notch of the flange 31. The weight of the plank and the workmen thereon is carried by the plank support 33 and therefore the strain applied to the head 15 of the device is outwardly or against the rails of the ladder from the rear.

55 With the construction shown and described, strain on the bracket is mostly imparted to the rails of the ladder, relieving the rungs of strain to a large degree. While 100 there is naturally strain applied to the stem or leg of the device, this is distributed over a number of rungs, due to said stem or leg being of considerable length so as to extend a distance along the length of the ladder. 105 The strain so applied to the rungs is inconsiderable compared to the strain at the upper end of the bracket, due to the fact that the entire supporting-portion, comprising the arm or plank-support 33, and brace 110 34, swings on the retainer pin 43, and the plank-support pulls outwardly under weight.

60 Having thus described my invention, what I claim is:—

1. The combination with a ladder having rails and rungs connecting said rails, of a bracket comprising a securing member formed of two parts, one part comprising a flat transverse portion having a depending leg 120 between its ends, retainer ears extending rearwardly therefrom at one end and a U-shaped rail-engaging member at its other end, the other part comprising a flat transverse portion lying against the rear of said first mentioned flat transverse portion between the retainer ears thereof and having a longitudinal slot and a rail-engaging member at its outer end, a bolt extending through said slot and through said first-mentioned flat 125 130

transverse portion, a plank support pivotally connected to said leg adjacent said first-mentioned flat transverse portion, and a brace pivotally connected to the outer end 5 of said plank support and having adjustable connection with said leg.

2. The combination with a ladder having rails and rungs connecting said rails, of a bracket comprising a support having a head 10 provided with rail-engaging ends and a leg depending from said head provided with a hook adapted to engage one of said rungs, said leg having a forwardly-extending flange provided with obliquely-disposed 15 notches and spaced forwardly-extending ears adjacent said head, a plank support having a forked inner end pivotally connected to said ears, a brace pivotally connected to the outer end of said plank support 20 and having a forked inner end, and a pin extending through the forked inner end of said brace and adapted for engagement with one of said notches.

3. The combination with a ladder having 25 rails and rungs connecting said rails, of a bracket having a securing member provided with a transversely-adjustable head equipped with rail engaging ends adapted to engage said rails and a stem depending from said 30 head having laterally-extending arms near said head and forwardly extending ears at

the outer ends of said arms, said leg having a forwardly extending flange along a portion of one of its edges provided with a series of notches, a plank support having a 35 forked inner end pivotally connected with said ears, and a brace pivotally connected to the outer end of said plank support and having means to engage any one of said series of notches.

4. A bracket for ladders comprising a securing portion having a transversely-disposed upper member provided with forwardly-opening U-shaped portions adapted to engage opposite rails of a ladder and a leg 40 extending downwardly from said transversely-disposed upper member and provided near its upper end with forwardly extending spaced ears and with a forwardly-directed flange along one edge thereof having a series of obliquely-disposed notches 45 therein, said leg having also downwardly opening hooks stamped therefrom and extending from the inner or rear face thereof, a plank support pivotally connected at its 50 inner end to the ears of said leg, and a brace pivotally connected to the outer end of said plank support and having a notch-engaging pin at its inner end adapted to engage any one of said series of notches. 55

In testimony whereof, I affix my signature.

LOUIS P. REIMANN.
